UNITED STATES PATENT OFFICE.

HENRY A. GARVEY, OF DETROIT, MICHIGAN, ASSIGNOR TO PACKARD MOTOR CAR COMPANY, OF DETROIT, MICHIGAN, A CORPORATION OF MICHIGAN.

GEAR-CUTTING MACHINE.

1,169,086.

Specification of Letters Patent.

Patented Jan. 18, 1916.

Original application filed June 24, 1913, Serial No. 775,558. Divided and this application filed June 1, 1914. Serial No. 842,144.

To all whom it may concern:

Be it known that I, HENRY A. GARVEY, a citizen of the United States, and resident of Detroit, Wayne county, State of Michigan, have invented certain new and useful Improvements in Gear-Cutting Machines, of which the following is a specification.

This application is a division of application Serial No. 775,558, filed June 24, 1913.

10 The present invention relates to gear cutting machines and more particularly to certain improvements whereby bevel gears having curved teeth are adapted to be cut on these machines.

15 One of the objects of the invention is to provide a simple, rigid construction for moving the tool accurately in a curved path.

Another object is to provide a construction which is not subject to excessive wear.

20 A further object is to provide an improved means for lifting the tool out of the tooth space on the return movement.

Other objects and the features of novelty will be apparent from the following description, taken in connection with the drawings, in which:

Figure 1 is a fragmentary plan view of the tool operating mechanism of a gear cutting machine embodying my improvements; 30 Fig. 2 is a front elevation of the same; Fig. 3 is an elevation of the left hand side of Fig. 2; Fig. 4 is a fragmentary section on the line 4—4 of Fig. 1; and Fig. 5 is an enlarged sectional view of the shaft for lifting the tool on the return stroke.

Referring to the drawings, 10 indicates the bed of the machine on which slides a ram 11, suitable guides 12' being provided for the ram. At its forward end the ram 11 carries a head 12 having a slide-way 13 for a tool support 14, the slide-way being arranged at right angles to the direction of movement of the ram. Any suitable means may be provided for securing the tool support 14 in the slide-way 13 and for this purpose I prefer to use the usual dove-tail on the tool support and form the slide-way to suit this dovetail, as indicated in dotted lines in Fig. 3. The tool support carries a rock shaft 15 which has secured thereto, by means of a pin 16, a tool holder 17. The tool holder 17 has a forwardly projecting arm 18 which carries the tool T and the arm 18 is

arranged between suitable guides 19 on the tool support.

55 The ram 11 carries a wrist pin 20 which is operatively connected with a crank pin 21 by means of a connecting rod 22. The crank pin 21 is adjustably secured in any well known way in the transverse slot 23 in the end of the hub 24 of a driving wheel 25, this driving wheel being arranged on a driving shaft 26, which is supported in suitable bearings (not shown).

For the purpose of guiding the tool T in 65 the arc of a circle I arrange on one side of the tool support 14 ears 27 to which an arm or link 28 is connected as by means of a suitable pivot pin 29. The arm or link 28 is also connected with a normally fixed pivot 30 70 which is arranged at one side of and slightly in advance of the pivot 29, as clearly shown in Fig. 1. The pivot 30 is carried by ears 31 on a wedge block 32, this wedge block being arc shaped and supported in a guide 75 33. The guide 33 is carried by a table 34 on a suitable bracket 35 secured to the frame 10. Above the guide 33 is a guide 36 which engages the block 32 and is adapted to be clamped against the latter by means of 80 screws 37. The guides 33 and 36 are arc shaped, as shown in Fig. 1, and have secured thereto the end plates 38 and 39 which carry adjusting screws 40 and 41, respectively. These screws engage the ends of the block 32 85 and are for the purpose of adjusting the latter in the guides 33 and 36.

For the purpose of raising the tool out of the tooth space on the return stroke of the ram, I arrange on one end of the shaft 15 90 a finger 42 which is adapted to be engaged by a finger 43 on a shaft 44. From the drawings it will be obvious that when the shaft 44 is rocked the finger 42 will be lifted and thus rock the shaft 15. The arm 18 of the 95 tool holder 17 will be lifted by rocking the shaft 15 and thereby carry with it the tool T, to a sufficient height to lift the latter out of the tooth space of the gear which is being cut, this gear being indicated in Fig. 3 at 100 G, and being supported on a shaft G' which is carried by the frame of the machine and moved by any suitable mechanism to generate the teeth, an illustration of such mechanism being shown in U. S. Patent 105 No. 665,054. The shaft 44 has one end

splined in a gear 45, which is rotatably mounted in a suitable bearing 46 carried by the head 12 of the ram. The gear 45 is held in position in the bearing 46 by means of a suitable collar 47 and meshes with a bevel gear 48 which is also rotatably mounted in a suitable bearing in the head 12. The other end of the shaft 44 is provided with a recess 49 which receives a stud 50 carried by the tool support 14.

Owing to the sliding movement which the tool support 14 has relative to the head 12, it is necessary to spline the shaft 44 to the gear 45, and for the purpose of connecting the shaft 44 with the stud 50 in such a manner as to permit rotation of the shaft relative to the stud, I provide the recess 49 with annular grooves 51 and 52 which are adapted to receive the ends of the pins 53 carried in suitable recesses 54 in the stud 50. In order to hold the ends of the pins 53 in the grooves 51 and 52, springs 55 are provided in the recesses back of the pins 53. For the purpose of facilitating the removal of the shaft 44 from the stud 50 I provide the shaft with openings 56 which communicate with the grooves 51 and 52, as shown in Fig. 5, and permit the insertion of a device for pushing the pins 53 out of the grooves.

A shaft 57 is mounted in a bearing 58 carried by the frame 10 and is splined in the gear 48. The shaft 57 carries a bevel gear 59 which meshes with a segmental bevel gear 60 arranged on one arm of a rocking lever 61. The lever 61 is pivotally mounted at 62 on a suitable bracket 63 and carries a cam roller 64, which is arranged in a cam groove 65 in the side of the driving wheel 25. The cam groove 65 is of such shape as to give the proper rocking movement to the shaft 44 to lift the tool T out of the tooth space when the ram starts on its return stroke.

It will be seen that the mechanism for lifting the tool out of the tooth space is comparatively simple and does not interfere in any way with the operation of the tool support.

In order to insure the return of the tool holder to the proper position for the forward or cutting stroke, I arrange on the arm 18 a laterally projecting post 66 to which is connected one end of a spring 67, the other end of this spring being secured to the post 68 on the tool support.

For the purpose of effecting a relative adjustment of the pivot 30 and the blank support to thereby vary the angle of the cut, I have provided the means for adjusting the block 32. It will be evident that the path of movement of the tool will depend on the relation of the pivot 30 to the pivot 29 and by shifting the block 32 by means of the screws 40 and 41 the pivot 30 which is carried by the block 32 will be adjusted relative to the pivot 29. When the pivot 30 is

in the proper position the screws 37 are tightened and the block 32 thus clamped. The block 32 is formed on an arc about the pivot 29 so that during the adjustment of the block the position of the tool support 14 will not be disturbed.

In the operation of the machine the reciprocation of the ram 11 causes the tool support 14 to move back and forth across the head 12, the pivot 29 which is carried by the tool support moving in an arc or oscillating about the pivot 30 as a center. The parts carried by the tool support 14 will move with it and the whole support will therefore move in a curved path, the motion being one of pure translation.

While I have shown and described what I now consider to be the preferred form of my invention, it will be understood that various changes can be made in the details of construction within the scope of the claims, and therefore I do not wish to be limited to the exact details shown and described.

Having thus described my invention, what I claim and desire to secure by Letters Patent is:

1. In a machine of the class described, the combination of a reciprocating head, a tool support carried by the head and having a tool holder adapted to be lifted from the work on the return stroke of the head, a pair of meshing bevel gears carried by said head, means actuated by one of said gears for lifting the tool holder, a shaft operatively connected with the other bevel gear and aligned therewith, a rocking lever, means for transmitting the movements to said shaft, and cam means operated in timed relation to the movements of the head for rocking said lever.

2. In a machine of the class described, the combination of a reciprocating head, a tool support carried by said head and having a tool holder adapted to be lifted from the work on the return stroke of the head, a pair of meshing gears carried by said head, means actuated by one of said gears for lifting the tool holder, a shaft operatively connected with the other bevel gear, a rocking lever carried by the frame of the machine, means for transmitting the movements of said lever to said shaft, and cam means operated in timed relation to the movements of the head for rocking said lever.

3. In a machine of the class described, the combination of a reciprocating head, a tool support carried by said head and having a tool holder adapted to be lifted from the work on the return stroke of the head, a pair of meshing bevel gears carried by said head, a shaft carried at one end of the tool support and at the other end in one of said gears, means whereby the tool holder is lifted by a rocking movement of said shaft, a second shaft supported on the frame of the

machine and having a sliding connection with the other of said gears, a bevel gear on said second shaft, a rocking lever having teeth engaging said last mentioned gear, and 5 cam means operated in timed relation to the movements of the head for rocking said lever.

4. In a machine of the class described, the combination of a reciprocating head, a tool support carried by said head and having a tool holder adapted to be lifted from the work on the return stroke of the head, means for reciprocating the tool support transversely of the head, a pair of meshing bevel 10 gears carried by the head, a shaft having one end supported on said tool support and its other end operatively connected with one of said gears, the shaft being slidable through said gear as the support is reciprocated on 15 the head, means whereby the rocking of said shaft is adapted to lift the tool holder, and means for actuating the other of said bevel gears.

5. In a machine of the class described, the combination of a reciprocating head, a tool support carried by said head and having a tool holder adapted to be lifted from the work on the return stroke of the head, means for reciprocating the tool support on the 20 head and means for lifting the tool holder comprising a stub shaft on the support, a shaft rotatably supported by said stub shaft and movable with the support, an operating gear carried by the head and having a sliding connection with the second mentioned shaft, a coöperating means movable with the tool holder and the second mentioned 25

shaft adapted to lift the tool holder when the second mentioned shaft is rocked.

6. In a machine of the class described, a 40 tool support, a tool holder pivotally mounted thereon, a stub shaft carried by the tool support, a shaft carried by said stub shaft and rotatable thereon, coöperating means on the tool holder and the second mentioned shaft 45 for lifting the tool holder when the second mentioned shaft is rocked, and means for rocking the second mentioned shaft.

7. In a gear cutting machine, in combination, the frame or bed, a sliding ram thereon, means for operating it, a tool support mounted to slide transversely of said ram, a pivoted tool holder on said support, and means for intermittently raising said tool holder comprising sliding connections from 50 said support to said ram and from the ram to the frame.

8. In a gear cutting machine, in combination, the frame or bed, a sliding ram thereon, means for operating it, a tool support 60 mounted to slide transversely of said ram, a pivoted tool holder on said support, and means for intermittently raising said tool holder comprising sliding connections from said support to said ram and from the ram 65 to the frame, and gears between said sliding connections.

In testimony whereof I affix my signature in presence of witnesses.

HENRY A. GARVEY.
